UNITED STATES PATENT OFFICE.

WILLIAM F. SCHWEIGERT, OF BUFFALO, NEW YORK.

CLOSURE FOR CONTAINERS.

Application filed September 17, 1925. Serial No. 56,893.

This invention relates to containers for liquids semi-liquids, powders, etc., and closures therefor.

Containers for paints, oils, putty, as well as fine powders, etc., should be provided with air-tight leak-proof closures so that they can be shipped and stored without leakage or evaporation. The closure should also be securely seated so that rough handling cannot dislodge or loosen it, and yet it should be readily removable to permit of easy access to the contents of the container. Again, after the closure has been removed it should be possible to replace it quickly and easily and in its original leak-proof condition. Various closures purporting to fulfill these requirements have been proposed but these, if successful, have involved the use of relatively expensive securing means which has limited their field of usefulness.

It is the object of the present invention to provide a container having a closure possessing the attributes given above, and which is simple to use and inexpensive to manufacture. I attain this object by providing the upper edge of the container with a double bend, spacing the outer two walls or plies thereof apart to form an annular groove for the reception of a depending flange on the cover, and providing at the base of this annular groove a series of spaced slots which receive similarly spaced lugs or tongues on the cover flange. After the cover is seated these tongues are bent outward thus firmly seating the cover on the body of the container and at the same time securely locking it in place. In order to insure a leak-proof joint I place a packing ring adjacent the base of the flange on the cover.

In order that the invention may be more clearly understood, I have illustrated certain preferred embodiments of it in the accompanying drawings in which Figure 1 is a side elevation, partly in section, of a container equipped with the closure of the present invention, the cover being illustrated slightly above the body of the container and in readiness to be placed in position; Figure 2 is a vertical section through the top of the container showing the cover in position; Figure 3 is a fragmentary plan view of the cover receiving groove on the body; Figure 4 is a fragmentary section similar to Figure 2 showing a modified form of cover in position, and Figure 5 is a fragmentary verti-

cal section through a modified form of the body.

Referring first to Figures 1, 2 and 3, 1 represents the body of a container, preferably made of sheet metal and cylindrical in form. The upper end of the cylindrical wall of this body member is provided with a double bend, the inner walls or plies of which are in contact while the outer ply is spaced somewhat from the intermediate forming an annular groove 2 which encircles the top of the container and lies external thereof. The body is thus provided with an inner top edge 3 and an outer top edge 4. The bottom of this groove 2 is provided with a series of spaced slots 5 which extend throughout its entire circumference.

The container is provided with a cover 6, the periphery of which is bent to form an inverted groove 7 the outer wall or flange 8 of which extends downward beyond the inner wall and fits snugly within the annular groove 2 on the body. This flange 8 is provided, around its lower edge, with a series of spaced lugs or tongues 9 which extend through the spaced slots 5 in the base of the groove 2 when the cover is in position, and at the same time the inner top edge 3 of the body lies within the groove 7 and is embraced thereby. At the bottom of the groove 7 I place an annular strip of packing 11 which bears against the inner upper edge 3 of the body when the cover is in position.

In order to secure the cover upon the body when in position, I bend the tongues 9 outwardly as illustrated on the left-hand side of Figure 2, thus clinching the cover upon the body and drawing the packing 11 snugly against the top edge 3. When it becomes necessary to remove the cover the tongues 9 are bent downward and the cover readily withdrawn.

In Figure 4 I have illustrated a modified form of cover in which the groove 7 terminates in a bead 12 reinforced by means of a ring 13.

In Figure 5 the outer wall of the groove 2 is made flush with the outer wall of the body, the inner wall being in consequence provided with a shoulder or off-set 14.

The container illustrated and described is simple to use and inexpensive to make. The closure itself consists of only two parts exclusive of the packing and there is nothing to get out of order or lost. The double bend

at the top of the body effectively reinforces that member and insures the retention of the original shape at all times, thus facilitating the removal and replacing of the cover. The 5 slotted holes at the base of the groove on the body make it impossible for this groove to become clogged with dirt or the contents of the container, and thus there is nothing to interfere with replacing the cover when 10 it is necessary to do so.

I claim:

In a container having separable body and cover members, the combination of a double bend in the wall of the body at its top

15 forming inner and outer top edges and an intermediate open annular groove, spaced slots in the bottom of the groove, an inverted annular groove on the periphery of the cover which embraces the inner top edge of the body when the cover is in position, 20 tongues depending from the outer wall or flange of the cover extending through the slots in the bottom of the body groove and packing at the bottom of the groove on the cover. 25

In testimony whereof I affix my signature.

WILLIAM F. SCHWEIGERT.
